Primary Examiner — Dana L Meyrow*(74) Attorney, Agent, or Firm* — Norton Rose Fulbright US LLP(57) **CLAIM**

We claim the ornamental design for a cosmetic bottle, as shown and described.

DESCRIPTION

FIG. 1 is a top perspective view of a first embodiment of our new design for a cosmetic bottle;

FIG. 2 is a front view of the bottle shown in FIG. 1;

FIG. 3 is a back view of the bottle shown in FIG. 1;

FIG. 4 is a right side view of the bottle shown in FIG. 1;

FIG. 5 is a left side view of the bottle shown in FIG. 1;

FIG. 6 is a top view of the bottle shown in FIG. 1;

FIG. 7 is a bottom view of the bottle shown in FIG. 1;

FIG. 8 is a top perspective view of a second embodiment of our new design for a cosmetic bottle;

FIG. 9 is a front view of the bottle shown in FIG. 8;

FIG. 10 is a back view of the bottle shown in FIG. 8;

FIG. 11 is a right side view of the bottle shown in FIG. 8;

FIG. 12 is a left side view of the bottle shown in FIG. 8;

FIG. 13 is a top view of the bottle shown in FIG. 8; and,

FIG. 14 is a bottom view of the bottle shown in FIG. 8.

The evenly-dashed broken lines in the drawings illustrate the portions of the cosmetic bottle that form no part of the claim.
